Primary Examiner — Janice Seeger*Assistant Examiner* — Martie K Holtje(74) *Attorney, Agent, or Firm* — Sunstein Kann Murphy & Timbers LLP(57) **CLAIM**

The ornamental design for a tethered flying stunt toy, as shown and described.

DESCRIPTION

FIG. 1 is a top, left front perspective view of a tethered flying stunt toy showing my new design;

FIG. 2 is a bottom, left front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The elements depicted by broken lines in the views have been shown for the purpose of illustrating portions of the tethered flying stunt toy that form no part of the claimed design.
